UNITED STATES PATENT OFFICE.

EDWARD A. SPRING, OF PHOENIX, ARIZONA.

MOLD CHILL.

Application filed January 31, 1927. Serial No. 164,777.

My invention relates to a mold for founding metal and it has particular reference to a chill for manufacturing liners for ball and rod mills, the objects of the invention being 5 to provide a simple and inexpensive mold which will eliminate all skilled labor and save all material now needed and required in making sand molds, thereby reducing the cost of production of casted articles and 10 effecting a considerable economy in time.

Another object of the invention is to provide a permanent mold by which the articles or bodies founded will be uniform in weight and free from any of the imperfections 15 usually encountered in casting articles in sand molds.

The accompanying drawing illustrates a preferred form of embodiment of my invention and therein Fig. 1 is a plan view. Fig. 20 Fig. 2 is a sectional elevation, the section being taken on line 2—2 Fig. 1. Fig. 3 is a section taken on line 3—3 Fig. 1, looking in the direction of the arrow. Figure 4 is a plan view of a modified form, and Fig. 5 is a 25 sectional view on line 5—5 Fig. 4. Similar reference characters on the drawing denote similar parts. Referring particularly to the form of the embodiment of the invention which is shown in the drawing, my improved mold comprises generally two sections 30 1 and 2 formed for mutual co-operation to produce the design, shape or outline desired of founded articles or bodies, suitable means being provided to convey the 35 melted metal into the mold formed by sections 1 and 2.

The section 1, which is the base or bottom of the mold, is substantially rectangular and is preferably provided with longitudinal 40 and transverse members 3 and 4 respectively, which support the base 1; but it will be obvious that these supporting members 3 and 4 may be omitted. The section 1 is provided with front and rear upstanding walls 5 and 6 respectively, and the sides of same are open. The upper face 1^a of the section 1 constitutes the bottom of the mold imprint, which as shown in Figs. 3 and 5 is 45 narrower and shorter than the base section 1, providing thereby lateral plane surfaces 6' and a front plane surface 7, for purposes now explained. The section 2 or top section 50 is arranged for movement relative to the section 1, and for this purpose may be hingedly connected to the rear upstanding wall 6 of the section 1. This section 2 is pro-

vided with downwardly extending side walls 8 which, when the section 2 is closed upon the section 1, rest upon the plane surfaces 6' which adjoin the imprint face 1^a of the 60 bottom section 1. The front and rear of said section 2 are open, as shown in Figs. 2 and 5 the rear of said section 2 in the form shown in Figs. 1, 2 and 3 being arranged to be closed by the rear upstanding wall 6 of 65 the section 1, when the sections are in operative or closed position; and the front of said section 2 being arranged to be closed by a plate 9. This plate 9 is held in place against the front open end of the section 2 70 by wedge members 10, which are arranged to be inserted between projections 11, provided on said plate 9, and the front upstanding wall 5 of the section 1. The plate 9 is also provided intermediate the ends thereof 75 with spaced, outwardly directed lugs 12, between which is arranged to be set and removably held in place by wedges 13, a gate 14, the bottom of which is arranged to extend through an opening 9' in the bottom 80 of and preferably centrally of the plate 9. The gate 14 is provided with a sprue 14', and may be made either solid and of metal, sand or any other suitable material, or may be composed of sections, as shown in Figs. 85 1 and 3.

The section 2 as shown in Fig. 3 is formed to produce the shape, outline or design of the upper part of the founded product, and is provided with a tapering opening 15 90 which penetrates the top thereof for a core 16 of metal or sand to form in the finished casting an aperture for the accommodation of a bolt, screw or other device by which the product founded in the mold may be attached.

In the form of the invention illustrated in Figs. 4 and 5, where no hinged connection is provided between the top and the bottom sections 1 and 2 respectively, the open front 100 and rear of the section 2 is arranged to be closed by removable plates 9, which are adapted to be held against the respective open ends of the section 2 by wedge members 10. These wedge members are arranged to be inserted between projections 11, provided on the outside of the plates 9, and the upstanding walls 5 of the sections 1. Each of the closure plates 9 is provided with spaced outwardly directed lugs 12, and between these lugs 12 are arranged to be set 105 and held in place by wedges 13, gates 14, the 110

bottom of each of which is arranged to extend through an opening 9' provided in each of the plates 9 at the bottom and preferably centrally thereof. Each of the gates 14 is provided with a sprue 14', and may be composed of sections, as shown, or may be made solid and of any material desired. The latter arrangement of mold as described is very desirable for heavy work.

20 What I claim, is:

1. A mold comprising a base section having front and rear walls, a top section connected with said base section at one end thereof, and arranged for movement relative thereto, said top section being open at its respective ends and provided with downwardly extending side walls which are arranged to rest upon said base section and between the upstanding walls thereof, the rear upstanding wall of said base section arranged to close the rear opening of said top section, a removable closure for the front of said top section, means to hold said closure in position, and a removable gate having the bottom thereof extending through said closure.

2. A mold comprising a base having upstanding front and rear walls, a section hingedly connected at one end to said base and being of less longitudinal extent than said base, said section being open at its respective ends and having side walls arranged to rest upon said base and between the front and rear walls thereof, a closure for the front of said hinged section, means to secure said closure in position, a gate having the bottom thereof extending through said closure, and means to secure said gate in position on said closure.

3. A mold comprising a base having upstanding front and rear walls, co-operating mold section hingedly connected to said base, said section having open ends, one of which is arranged to be closed by the rear upstanding wall of said base, a removable closure

for the other end of said section, means to secure said closure in position, and a gate removably fastened to said closure.

4. A mold comprising a base having upstanding front and rear walls, a section co-operating with said base and connected therewith for relative movement, said section being open at its ends and arranged to fit between said upstanding walls whereby the rear open end of said section is closed by the rear wall of said base, a removable closure for the front open end of said section, said closure having a plurality of projecting lugs intermediate the ends thereof, a gate between said lugs and having the bottom thereof extending through said closure, and means to secure said gate in position.

5. A mold comprising two sections hingedly connected, one of said sections having front and rear walls and the other section having side walls arranged to rest upon said first named section and to engage the rear wall thereof, a closure for the front end of said other section, a gate having its lower end extending through said closure, and means to removably connect said gate with said closure.

6. A mold comprising a plurality of sections hingedly united for relative movement, the front of one of said sections being open, a removable closure for said open front, means engaging one of said sections and said closure to hold said closure in position, and a gate removably connected with and extending through said closure.

7. A mold comprising a base section having front and rear walls, a top section open at its respective ends and provided with downwardly extending side walls arranged to rest upon said base section, an end closure for said top section, and a gate associated with said closure.

In testimony whereof I have set my hand.

EDWARD A. SPRING.
